DESIGN FOR A RESTAURANT OR SIMILAR BUILDING

Frederick H. Jantzen, Bronx, N. Y.

Application October 11, 1938, Serial No. 80,362

Term of patent 14 years

To all whom it may concern:

Be it known that I, Frederick H. Jantzen, a citizen of the United States, residing at Bronx, county of Bronx, and State of New York, have invented a new, original, and ornamental Design for a Restaurant or Similar Building, of which the following is a specification, reference being had to the accompanying drawing, forming part thereof.

Fig. 1 is a top plan view;

Fig. 2 is a front elevation of the restaurant or similar building, showing my design.

I claim:

The ornamental design for a restaurant or similar building, substantially as shown.

FREDERICK H. JANTZEN.
